BRASSIÈRE

Harry Jay Dubner, Forest Hills, N. Y.

Application December 26, 1946, Serial No. 718,500

5 Claims. (Cl. 2—42)

1

This invention relates to garments such as foundation garments or brassières having bust pockets.

One object of the invention is to provide a garment of the nature set forth having improved means particularly adapted to fit, support and cause substantial separation of the bust, with especial reference to a relatively large bust.

Another object of the invention is the provision of a garment of the type mentioned having improved means which is self-adjusting to the bust in producing separation thereof.

Another object of the invention is to furnish a garment of the character described having improved means within the pockets thereof for urging the breasts apart from each other, and with the garment so constructed that the pockets are adapted to yield to accommodate the bust as separated or shifted therein.

More specifically it is an object of the invention to provide a brassière or the like having elements within the pockets thereof anchored so as to cause separation of the bust and so arranged in a floating manner as to be self-accommodating to the shape of the bust, to thereby produce maximum separation, with the brassière being adapted to yield intermediate of the pockets in such a manner that the pockets will accommodate the separated bust according to its particular size and shape.

Another object of the invention is the provision of a device of the class alluded to having few and simple parts, and being inexpensive to manufacture, neat in appearance and durable in construction and adapted to embrace the body of the wearer with the desired degree of tension.

Other objects and advantages of the invention will become apparent as the specification proceeds.

With the aforesaid objects in view, the invention comprises the novel features, combinations and arrangements of parts hereinafter described in their preferred embodiments, pointed out in the subjoined claims, and illustrated in the annexed drawing, wherein like parts are designated by the same reference characters throughout the several views.

In the drawing:

Figure 1 is a view in front elevation of a garment embodying the invention as laid out in relatively flat position and with portions of the shoulder straps removed and with the end fastening means omitted.

Fig. 2 is a sectional view taken approximately on the line 2—2 of Fig. 1.

2

Fig. 3 is a fragmentary view in rear elevation of the garment, but showing the same expanded.

The advantages of the invention as here outlined are best realized when all of its features and 5 instrumentalities are combined, but useful embodiments may be produced involving less than the whole.

It will be obvious to those skilled in the art to which the invention appertains, that the same 10 may be incorporated in several different constructions. The accompanying drawing, therefore, is submitted merely as showing a preferred exemplification of the invention.

Referring in detail to the drawing, 10 denotes 15 a garment such as a foundation garment, and more particularly a brassière embodying the invention. The same includes a body-embracing or bandlike member 11 having the bust pocket sections 12 and end sections 13, the latter adapted

20 to extend around the sides and back of the wearer to be fastened together in any well-known detachable manner which is not shown. Shoulder straps 14 may be provided to function in the conventional way. The sections 12 are provided

25 with bust pockets 15 which may have one or more cutouts as indicated at the seam 16 for producing the required cuplike form. These sections are seamed at 17 to the end portions 13. For a bust of substantial size, the pockets may

30 provide concavities of the required diameter and depth, which may be substantially greater than those herein shown. As thus far described, the garment may be conventional.

At the central, normal, relatively flat region 35 20 of the garment, the same is longitudinally yieldable in a relatively restricted manner, such yield being principally intermediate of the top line or point 21 and the bottom edge 22 of the brassière, and it is preferred that some yield

40 shall also occur at the bottom edge. Illustratively, this central region 20 is formed with a vertical, slot-like opening 23 between the bust pockets, this slot being closed at its upper end 24 and being desirably open at the bottom edge 22.

45 Spanning this opening is a longitudinal piece of fabric 25 preferably disposed at the rear face of the garment and so connected thereto as to permit relatively free and unrestricted expansion at a central point between the top and bottom edges 21 and 22. This member 25 is stitched or tacked as at 26 to the upper non-expandable portion of the garment, and is stitched or tacked as at 27 to the lower part of the garment near the bottom edge 22 and at opposite sides of the opening 23. The member 25 may be otherwise free

50 55

for unrestricted expansion of the garment intermediate of the stitching 26 and 27. With certain large busts it is desirable to permit some limited degree of expansibility along the bottom edge 22 for more effective accommodation of the bust in the pockets 15, and accordingly the member 25 may consist of material which is elastic lengthwise of the brassière. Only that portion of the member 25 near the bottom edge 22 is thus elastically effective, but for simplicity in manufacture, the entire member 25 may consist of a single piece of material having this characteristic.

Anchored at a point intermediate of the upper and lower stitching 26 and 27, and desirably rather centrally therebetween is a retaining element 30 for a purpose presently described. This element may consist of a strip of pliant material extending horizontally and being fixedly mounted for example on the member 25. It is preferred that this element 30 shall consist of material that is longitudinally elastic, and it extends laterally at least partially into the bust pockets 15. The mounting of the element 30 is desirably accomplished by stitching or tacking the same at 31 to the member 25 intermediate of the side edges of the latter. The element 30 is thus relatively free for stretching longitudinally without restraint by the member 25 or by any other part of the garment.

Disposed within each pocket 15 is the strip member 35 arranged in an arcuate manner adjacent to the central region of the brassière or with respect to the apices of the pockets as approximate centers. Each of these members is mounted at its ends on the bust pockets, for example by stitching or tacking thereto at 36 at the top of the pocket, and at 37 adjacent to the bottom of the pocket. The curve of each of these strip members 35 may be generally described as being such as to effectively engage the breasts for the best possible separation thereof. The strip members 38 may be arranged at opposite regions of the pockets being tacked at 39 and extending laterally and upwardly to be tacked at 40 to the pockets at points approximately at the elevation of the apices of the pockets. If desired, the strip members 35 and 38 may consist of continuous ribbons or bands, with those shown at 38 also serving as a support for the bust and to partially oppose the lateral urging of the breasts by the members 35. Except as herein described, the members 35 and 38 are free of the bust pockets so as to be self-forming to the size and shape of the bust. However, the strip members 35 are connected to the retaining element 30 in suitable manner. Such connection is best accomplished by forming the member 30 as a loop as shown, the members 35 freely passing through the end portions 41 of the loop member 30. Thus it is possible for the fullness of the member 35 to be adjusted by relative sliding movement thereof in the loop. Furthermore, the loop permits the adjacent portion of the member 35 to assume a twist or angular relation as indicated at 42 for an increased degree of lateral contact with the breast, the shape of the loop portions 41 changing to accommodate the position of the strip member 35. If desired, the strip members 35 and 38 may consist of longitudinally elastic material.

In use, the brassière affords particularly satisfactory fitting, support, and especially separation of relatively large busts, and in this regard it possesses a degree of self-adjustment which

has not to my knowledge been realized heretofore. While the practice is to make bust cups in certain sizes, it is not possible to manufacture on a quantity production basis too many sizes of bust cups, and accordingly adjustability becomes essential, especially for the relatively large bust. When the instant garment is applied to the wearer, the breasts are received into the bust pockets 15 with the curved bands 35 assuming at least in part an angular position for more effective lateral engagement with the breasts than may be accomplished by the pockets themselves. Thus a substantial separation of the breasts is obtained. This angularity is possible by reason of the lost motion connection of the members 35 in the loops 41, and further the fulness or distribution of the members 35 may vary up and down to fit the configuration of the breasts. The action just described is also facilitated by the stretchability of the element 30. The members 35 may alter more or less the relation of the breasts to the pockets 15, depending upon the size and shape of the breasts. To allow for this, the garment is expansible at the central region intermediate of the pockets; thus the opening 23 shown in normal position in Figure 1 may assume the configuration shown in Fig. 3. This longitudinal expansion of the garment results in a substantially increased fulness in the pockets at the inner region thereof indicated at 45, whereby in turn the members 35 may more effectively do their work. In the case of certain busts, it is also of advantage that some expansion, although in lesser degree shall occur adjacent to the lower edge 22, and this is permitted by the elasticity of the member 25, with the opening 23 extending to the bottom edge. Such elasticity must be rather limited in order that the bust pockets shall adequately support the breasts with a proper degree of tension of the brassière around the body of the wearer. The support of the breasts is of course greatly facilitated by the members 35 and 38 whereby the expansibility along the bottom edge 22 of the brassière becomes feasible. The members 38 may also assume an angularity for effective contact with the bottom region of the bust, but such angularity is much less than that of the members 35 at the element 30. Except as otherwise described, the garment may be made of any suitable materials well known in the art.

The brassière 10 will also function in a reversed manner, in other words, in the inside out position. In fact, the operation of the members 35 and 38 will be even more effective for their intended purposes if they are located on the external side of the brassière. This can be realized by the identical construction shown, for which purpose Fig. 3 may also be regarded as an outside view of the brassière, and the only change in arrangement would be that the twist in the members 35 and 38 would be reversed to follow the convex contour of the bust pockets in a natural manner, this change in twist being inherent in the construction shown by reason of the freedom which each of these members possesses intermediate of the points of securing at 36, 37, 39, and 40. The advantages referred to reside in the fact that these members 35 and 38 will act upon the breasts through the pocket walls, the latter serving to more uniformly distribute the tension imparted by the members 35 and 38 in separating and supporting the bust. The smooth texture of the pocket walls will permit these members 35 and 38 to automatically

slide therealong to assume their most desirable positions. Such automatic adjustment in the exterior position of the members is feasible in the case of member 35 if the latter is suitably anchored or restrained at points in relative proximity to each other as at 35, 41, and 37, these points being spaced apart according to an acute angle whose center is at the apex of the bust pocket. From the standpoint of appearance however, it is more desirable that the members referred to shall be concealed within the bust pockets. The term "within the pockets" and similar expressions in the appended claims are to be interpreted as meaning "within the area defined or subtended by the bust pockets," so as to include an external as well as an internal location of any or all of the members such as 35, 38, 25 and 30.

I claim:

1. A brassière comprising a body encircling band having an expandable central region and top and bottom edge borders, conical breast pockets spaced apart by said central region between said edge borders, said breast pockets each having an upper and lower region, a flexible strip element formed with an arcuate portion extending along the periphery of each pocket from said upper pocket region around towards said central region to said lower pocket region adjacent the bottom edge border for positioning breasts of the wearer each within a pocket, opposite ends of said strip element being secured to the respective pocket at each of said upper and lower pocket regions, said conical pockets having apices with said strip element arcuate portion curved to approximately correspond to arcs with said apices as centers, said expandable central region being formed with a slot-like opening between said top and bottom edge borders for varying the effective size of the pockets to accommodate spacing the breasts as positioned by said strip elements, a transverse member floatingly mounted in said expandable central region underlying and bridging said slot-like opening anchored at one end thereof to said top edge border and at the other end to each of the pockets adjacent said bottom edge border, and a pair of loop members carried by said transverse member at a midportion thereof, said loop members extending in opposite directions each toward a pocket and engaging said strip elements to permit movement of the latter in conforming to convex surfaces of said breasts for self-adjustment as required by fullness and spacing thereof.

2. A brassière comprising a body encircling band having an expandable central region and top and bottom edge borders, conical breast

pockets spaced apart by said central region between said edge borders, an arc-shaped flexible strip element positioned along an inner side of each of the pockets about the periphery thereof, said strip being connected to each of the pockets at the top, bottom and periphery remote from said central region, said strip elements being otherwise free from the pockets to position the breasts within said pockets, said expandable central region having a slot-like opening extending between said top and bottom edge borders for varying the effective size of the pockets to accommodate spacing the breasts positioned by said strip elements, a transverse member floatingly mounted in said expandable central region underlying and bridging said slot-like opening anchored at one end thereof to said top edge border and at the other end to each of the pockets adjacent said bottom edge border, and oppositely positioned loop members carried by said transverse member at a midportion thereof through slip engagement with said strip elements to permit movement of the latter to conform to convex surfaces of the breasts for self-adjustment to requirements of fullness and spacing thereof.

3. The brassière as defined in claim 1 in which said strip elements are made elastic for longitudinal expansion.

4. The brassière as defined in claim 1 in which said transverse member is elastic across the width thereof to permit expansion of the brassière band at the bottom edge border and separation of the spacing of said pockets thereat.

5. The brassière as defined in claim 2 in which said strip elements are made longitudinally elastic, and said transverse member is elastic across the width thereof to permit expansion of the brassière band at the bottom edge border and separation of the spacing of said pockets thereat.

HARRY JAY DUBNER.
